UNITED STATES PATENT OFFICE

159,346

SPECTACLE FRAME OR THE LIKE

Severin Jonassen, New York, N. Y., assignor to
American Optical Company, Southbridge,
Mass., a voluntary association of Massachusetts

Application December 16, 1948, Serial No. 150,184

Term of patent 14 years

(Cl. D57—1)

To all whom it may concern:

Be it known that I, Severin Jonassen, a citizen of the United States of America, residing at New York, in the county of New York and State of New York, have invented a new, original, and ornamental Design for a Spectacle Frame or the like, of which the following is a specification, reference being made to the accompanying drawings, forming a part thereof.

Fig. 1 is a perspective view of a spectacle frame, showing my new design;

Fig. 2 is a front elevational view of the spectacle frame shown in Fig. 1; and

Fig. 3 is a side elevational view thereof.

The characteristic features of my design are shown in full lines in the drawing and embrace a spectacle front embodying a pair of relatively wide rims having their upper walls converging

and blending with an integral bridge portion to produce a shallow V-shaped appearance and with the nasal portions of the rims terminating in spaced ears positioned to the rear of and having the effect of protruding above the base of the V.

I claim:

The ornamental design for a spectacle frame or the like, substantially as shown and described.

SEVERIN JONASSEN.
